UNITED STATES PATENT OFFICE.

WILLIAM E. HAYNES, OF SOMERVILLE, NEW JERSEY.

DESIGN FOR A BADGE.

SPECIFICATION forming part of Design No. 28,517, dated April 26, 1898.

Application filed March 12, 1898. Serial No. 673,662. Term of patent 8½ years.

To all whom it may concern:

Be it known that I, WILLIAM E. HAYNES, a citizen of the United States, residing at Somerville, in the county of Somerset and State of New Jersey, have invented and produced a new and original Design for Badges; and I do hereby declare the following to be a full, clear, and exact description of the same, reference being had to the accompanying drawing, forming a part thereof.

The drawing is a front view of a badge, showing my design.

The leading feature of my design consists in the perspective representation of a battle-ship resting upon water and located on the upper third of a three-color piece of ribbon, and above it a rectangular panel, said panel being surmounted by the representation of two American flags, the staffs of which are laterally inclined in opposite directions, and upon them rests an eagle having its wings spread out laterally and downwardly.

The ribbon of the badge has three stripes of equal width lengthwise thereof, a red stripe

on one side, (represented at A,) a white stripe 25 B in the middle, and a blue stripe C on the opposite side. At the bottom ends of said stripes there is a fringe F. Upon the upper third of the ribbon there is located a perspective view of a battle-ship D, resting upon wa- 30 ter, and above it a rectangular panel E, ex- tended across the whole width of the badge. On top of the panel E there is the representation of two American flags f, the staffs g of which are laterally inclined in opposite di- 35 rections, and upon them rests an eagle d, hav- ing its wings spread out downwardly and lat- erally nearly the whole width of the badge.

What I claim is—

The design for a badge as herein shown and 40 described.

In testimony whereof I affix my signature in presence of two witnesses.

WILLIAM E. HAYNES.
